PROCESS FOR TREATING HYDROCARBONS

Arthur Hallam Boulbee, Martinez, Calif., assignor to Shell Development Company, San Francisco, Calif., a corporation of Delaware

Application July 20, 1936, Serial No. 91,490

6 Claims. (Cl. 196—10)

This invention relates to the production of aromatic and olefinic hydrocarbons and hydrogen from mineral oils containing substantial amounts of naphthenic hydrocarbons and is particularly concerned with a new combination of treating steps for producing high yields of valuable products.

Certain mineral crude oils, as California, Venezuela, Gulf Coastal, Columbian, etc. crudes or distillates and/or solvent raffinates therefrom may contain besides aliphatic and aromatic hydrocarbons substantial amounts of naphthenes. Certain fractions, produced from crudes of this type, for instance light or middle oils such as naphtha, kerosene, gas oil, etc. which have a high naphthene content, may be of relatively little value. For example, a gasoline distillate produced from a California crude may have been stripped of its aromatic hydrocarbons which are used in the manufacture of solvents. The remaining distillate in spite of its high content of naphthenes, having a low octane number and poor solvent quality, is generally quite undesirable.

It is the purpose of my invention to treat such oils in a manner so that they are converted almost entirely to hydrogen, aromatic hydrocarbons, and low-boiling olefines. Olefines produced in my process may be used to alkylate the aromatics or may be polymerized to gasoline, lubricating oil or rubber-like polymers; undesirable polymer fractions may be separated, if desired, and be depolymerized to olefines, the latter being returned for repolymerization to more desirable polymers; the hydrogen or part of it may be utilized to hydrogenate suitable polymers, thereby stabilizing them and in the case of gasoline raising its antiknock value; and the aromatic hydrocarbons may be used as gasoline, tractor fuel, solvents, or as starting material for the manufacture of a large variety of derivatives including lubricating oils, dyes, explosives, pharmaceuticals, etc.

My process comprises catalytically dehydrogenating a suitable naphthenic oil under conditions to dehydrogenate the naphthenes only, thereby converting them to aromatic hydrocarbons and to leave aliphatic hydrocarbons substantially intact, separating the hydrogen so produced, subjecting the remaining oil to a cracking process to convert as large as possible a portion of the aliphatic hydrocarbons to lower boiling olefines and paraffins, and separating the resulting cracked mixture to produce a relatively heavy aromatic fraction, a lighter aliphatic

fraction containing a substantial proportion of olefines, and a tar.

Catalytic dehydrogenation of hydrocarbon oils containing naphthenes and aliphatic hydrocarbons to produce aromatic hydrocarbons is known. As catalysts may be employed, for example, metals such as silver, copper, iron, nickel, cobalt, aluminum or alloys thereof; or sulfides or oxides of iron, nickel, cobalt, zinc, cadmium, aluminum, lead, bismuth, tin, vanadium, etc. Particularly active are catalysts consisting of or containing oxides or sulfides of the metals of the sixth group of the periodic system, namely of chromium, molybdenum, tungsten, uranium, selenium, tellurium, and polonium. Sulfides, being in general more resistant to catalyst poisoning than oxides or other types of compounds, are preferred. The catalysts may be used alone or in admixture with each other and deposited on solid carriers if desired. As carriers silica, various silicates such as pumice, clay, brick, unglazed tile, asbestos, or porous carbon such as charcoal or metallurgical coke may be used.

Effective dehydrogenation temperatures vary considerably with the activity of the catalyst, the more effective catalysts being active at temperatures between about 200° to 500° C. while the less active catalysts may require temperatures between 500° and 700° C. To avoid cracking of the aliphatic hydrocarbons in the dehydrogenation zone with consequent formation of fixed hydrocarbon gases, such as methane, and of olefines which are undesirable in this step, I usually select catalysts which are active below about 500° C. Olefines, if allowed to form, tend to gum up the catalyst and render it inactive, while methane and the like contaminate the hydrogen, making it less valuable.

The activity of many of the catalysts may be greatly prolonged by the presence of from about 30 to 80 cubic feet reduced to normal of hydrogen per gallon of liquid oil to be dehydrogenated. If dehydrogenation is carried out in the vapor phase the hydrogen partial pressure in the vapors before dehydrogenation may advantageously range from about 30 to 80% of the total pressure. Hydrogen produced in the dehydrogenation may be used by simply recirculating a portion thereof through the dehydrogenating zone. Instead of hydrogen, a gas containing hydrogen may be used, if desired. Oxidizing gases such as air, carbon dioxide, etc. should, however, be excluded.

The effect of the hydrogen seems to be that of selectively suppressing dehydrogenation of

paraffinic hydrocarbons to olefines. Olefines, as pointed out, tend to polymerize and gum up the catalyst. The presence of oxidizing gases apparently has the opposite effect, the result being olefine formation and a reduction of the life of the catalyst.

Dehydrogenation may be carried out in the liquid or the vapor phase, depending upon the operating temperatures involved and the boiling range of the fresh feed. In general, I prefer vapor phase dehydrogenation, as it seems to be more efficient, and the catalysts have longer lives. Pressures of the order of about 10 to 100 pounds per square inch were found to give good results.

Since it is the aim selectively to dehydrogenate naphthenes without substantially cracking paraffins, it is obvious that if dehydrogenation temperatures are employed which are above the incipient cracking temperatures of the paraffins contained in the oil under treatment, the time allowed for the dehydrogenation must be sufficiently short, so as to prevent substantial cracking. The rates of cracking for paraffins for various boiling ranges over a wide temperature range are known approximately (Genessee and Reuter, Ind. Eng. Chem. 1932, 24, page 219) and from these rates the time allowable to effect not more than a limited amount of cracking can readily be estimated. Since at temperatures below about 700° C. and in the presence of effective dehydrogenation catalysts, the rate of dehydrogenation of naphthenes is invariably ever much greater than the cracking of paraffins, a substantial amount of dehydrogenation can be effected within the time limited so as to prevent substantial cracking.

It is usually a question of economy as to how far paraffins may be cracked in the dehydrogenation step. The maximum allowable per cent cracking may vary within fairly wide limits but in most instances should be kept below about 5% and preferably below about 2%.

Incipient cracking temperatures for normally liquid paraffin hydrocarbons are believed to lie between about the limits of 375° to 415° C., high boiling hydrocarbons generally having lower incipient cracking temperatures than lower boiling hydrocarbons.

One of the objects of my process is to produce aromatic hydrocarbons of a high degree of purity from mineral oils. The degree of purity which can be achieved by dehydrogenation alone depends on the concentration of the naphthenes in the initial material. Hydrocarbon oils, however, as produced commercially never consist altogether of naphthenes, but contain varying amounts, usually 50% or more of aliphatic and aromatic hydrocarbons. For instance, California gasolines have been found to contain 35 to 45% naphthenes, while Mid-Continent gasolines contain about 15 to 30%. Since the aromatic hydrocarbons resulting from dehydrogenation of naphthenes boil at about the same temperatures, it is difficult to separate by distillation such aromatic and unchanged naphthenes and aliphatic hydrocarbons contained in the products of dehydrogenation. To facilitate the concentration of aromatics by separating non-aromatics therefrom, I convert aliphatic hydrocarbons and unchanged naphthenes to lower boiling olefines, by subjecting the de-hydrogenated mixture to a non-catalytic cracking process without first separating aliphatic and aromatic hydrocarbons from each other. In this cracking step conditions are maintained, so that as large a

portion as possible of the non-aromatic hydrocarbons is converted to lower boiling products, while aromatic hydrocarbons remain substantially unchanged, except for the possible loss of some alkyl side chains and a small amount of condensation to higher boiling poly-aromatic compounds such as pyrene, chrysene, or homologues, etc. The cracking is advantageously carried out at an effective cracking temperature of the order of 500° to 750° C. and preferably in the vapor phase at relatively low pressures, for instance below about 200 pounds per square inch, although pressures up to 1500 pounds may be used. The time of exposure to cracking temperatures is measured by the cracking per pass of the aliphatic hydrocarbons, cracking per pass being herein defined as the percent of aliphatic hydrocarbons converted to compounds boiling without, i. e. below or above, the boiling range of the aromatic fraction, which boiling range is usually substantially identical with that of the initial oil. Since during the cracking operation a certain amount of polymerization of olefines to polymers which may boil within the original boiling range is unavoidable, it is advantageous to use in my process relatively narrow fractions, because there will be less chance for the formation of polymers which boil within the boiling range of the original fraction. Hence the cracking per pass, under otherwise identical conditions, must be greater for a relatively narrow original fraction than for a wider one. To realize the fullest advantage of my invention I therefore prefer to use, as initial material, fractions which have an A. S. T. M. boiling range of not more than about 50° C.

It is of some importance that in the cracking step the oil be heated from incipient cracking temperature to the effective cracking temperature in the shortest time possible and that at the end of the cracking reaction the cracked mixture be shock chilled. Slow heating to the effective cracking temperature and failure to shock chill may cause polymerization of olefines to tar or to non-aromatic compounds which may boil within the boiling range of the aromatic fraction. Low boiling olefines being desired in my process for the manufacture of valuable synthetic products, this premature polymerization during the cracking operation should be avoided.

Depending upon the type of olefines desired, the effective cracking temperature may vary within the limits indicated above, higher temperatures in general tending to produce lower boiling olefines.

The cracked mixture produced in the cracking step is usually fractionated to separate a fraction having approximately the boiling range of the original oil consisting predominantly of aromatic hydrocarbons, a lighter fraction comprising olefines and paraffins, and a tar fraction. The tar is withdrawn and may be used as fuel, road oil, etc. The aromatic fraction may be used as solvent or as blending agent for gasoline or tractor fuel, or it may be refractionated and/or refined in various ways so that pure compounds, such as benzene, naphthalene, anthracene or their homologues such as alkyl derivatives may be prepared therefrom.

In an alternative procedure the cracked mixture is freed from tar and excessively volatile components such as methane, ethane, etc. by distillation, and the resulting distillate, which may or may not contain normally gaseous components, is subjected to a selective solvent extraction under conditions to separate essentially paraffins and

naphthenes from aromatics and olefines. The paraffinic fraction is preferably returned to the non-catalytic cracking zone and the aromatics and olefines fraction may be further separated by 5 distillation and/or solvent extraction, or the mixture may be treated with a condensing reagent such as phosphorous pentoxide, phosphoric acid, sulfuric acid, aluminum chloride, etc. to react the olefines and aromatics with each other, thereby 10 producing alkylated aromatics suitable for anti-knock gasoline, lubricating oils, pour point depressors, etc.

If the distillation of the cracked mixture is carried out in accordance with the usual procedure, 15 the fraction comprising olefines is further fractionated to produce a light gas consisting essentially of ethane and lighter, which is discarded, a heavier normally gaseous fraction consisting mainly of 3 to 5 carbon hydrocarbons, and a normally liquid non-aromatic fraction comprising 20 the heavier than pentane hydrocarbons; if desired, part or all of the five carbon hydrocarbons may be combined with the normally liquid fraction. The 3 to 5 carbon fraction is subjected to a 25 polymerization to produce any desired polymer. For instance, it may be treated with phosphoric acid or the like to produce dipolymers suitable for gasoline, or with aluminum chloride to produce lubricating oils, or with boron fluoride to 30 produce rubber-like polymers suitable for blending with lubricating oils. These polymers may be fractionated and be stabilized by hydrogenation, using hydrogen produced in the dehydrogenation step.

The heavier normally liquid non-aromatic fraction 35 containing a considerable proportion of olefines may be returned to the non-catalytic cracking zone if desired. Due to the danger of converting the olefines in the cracking zone to 40 polymers which may boil within the boiling range of the aromatic fraction, I prefer, however, to make use of one of two alternative methods for further cracking this fraction. I may subject the entire fraction to a catalytic vapor phase cracking 45 process; or I may extract the fraction by selective solvent extraction under conditions to separate olefines from paraffins or treat it in some other manner to separate saturated from 50 unsaturated hydrocarbons, returning the paraffins to the non-catalytic cracking zone and cracking the olefines catalytically.

At suitable elevated temperatures and in the presence of certain catalysts, olefines break down to lower boiling hydrocarbons more readily than 55 do paraffins. By maintaining relatively mild cracking conditions, olefines may be cracked or depolymerized to lower boiling olefines without being substantially polymerized, while paraffins remain largely unchanged. By a subsequent 60 fractional distillation the lower boiling olefines may then be separated from unchanged paraffins, the latter being returned to the non-catalytic cracking treatment, while the 3 to 5 carbon olefines fraction is combined with a similar fraction 65 produced in the non-catalytic cracking treatment, the combination to be polymerized.

Products of polymerization usually are mixtures of more or less desirable polymers. Heretofore 70 undesirable polymers constituted a loss. In my process, however, I return undesirable polymer fractions, after separating them by distillation, fractional extraction, etc. to the catalytic cracking treatment where they are depolymerized to low boiling olefines, the latter then being again 75 polymerized to polymers, at least a portion of

which is of the desirable type. In this manner I substantially increase the yield of the desirable polymers.

Since my process is not concerned with the manufacture of any particular polymers, reference 5 is made to the prior art with respect to what polymers are deemed desirable or undesirable. For instance, if it is attempted to produce gasoline by polymerization, polymers boiling within the gasoline boiling range are desirable, 10 while higher boiling polymers are obviously undesirable; or if lubricating oils are to be produced, polymers of a lubricating viscosity are desirable, while less viscous polymers are undesirable.

For cracking catalysts a large variety of substances 15 may be used, for instance acidic oxides or hydroxides such as boron oxide, alumina, silica, titanium oxide, stannic oxide, phosphorus pentoxide, phosphoric acids, molybdenum oxide, selenium dioxide, tellurium dioxide, etc.; or acidic 20 clays such as fuller's earth or acid activated bleaching clays; or anhydrous inorganic halides which upon addition of water liberate hydrogen halide, for instance aluminum chloride, titanium chloride, zinc chloride, stannic chloride, phosphorus 25 trichloride, phosphorus oxychloride, antimony trichloride, bismuth chloride, vanadyl chloride, chromium chloride, ferric chloride, etc.

The time and temperature of exposure to the catalyst to obtain suitable conversion depends 30 a great deal on the cracking catalyst used. Temperatures between about 300° to 600° C. are usually suitable. Pressures may vary from substantially atmospheric to about 200 pounds per square inch, low pressures normally being conducive to 35 the formation of olefines. For instance when passing a mixture of duodecane and duodecylene over a calcined catalyst comprising phosphoric acid deposited on silica at a space velocity of one liquid volume of mixture per volume of catalyst 40 per hour at 350° C. and substantially atmospheric pressure, a predominating portion of the olefines was broken down to C₃—C₈ hydrocarbons, while the paraffins remained largely unchanged.

The aforementioned extraction of the non- 45 aromatic fraction comprising normally liquid hydrocarbons may be carried out with any of the known selective solvents which are capable of separating paraffins from olefines, such as liquid sulfur dioxide, ββ' dichlor ethyl ether, furfural, nitrobenzene, phenol, cresilic acids, acrylic aldehyde, croton aldehyde, etc. Conditions of extraction should be chosen so that the raffinate, which returns to the non-catalytic cracking zone, 50 is substantially free from olefines for reasons 55 already pointed out. The presence of paraffins in the extract is not usually harmful.

My process may be more fully understood from the description of the accompanying drawing representing a flow diagram of the new process. 60

Heated naphthenic oil, preferably of narrow boiling range, enters from a source not shown, through line 1 into evaporator 2 where it may be completely vaporized or be fractionated, if desired, to yield an unvaporized heavy fraction, 65 which is discarded through bottom line 3, and a vapor fraction. The latter passes through vapor line 4 to heating coil 5 in furnace 6, where it is heated to an effective dehydrogenation temperature between about 200° and 500° C. It then 70 proceeds through line 6' to dehydrogenator 7. The dehydrogenator contains a suitable dehydrogenation catalyst of the type hereinbefore described. A total pressure of about 10 to 100 75 pounds per square inch may be maintained in

the dehydrogenator, about 30 to 80% of which may be hydrogen partial pressure. Under these conditions the naphthenes in the vapors are dehydrogenated to aromatic hydrocarbons while 5 paraffinic hydrocarbons remain substantially unaffected, and olefines, if present, tend to be converted to paraffins. The dehydrogenated vapors are condensed in condenser 8 situated in line 9, and the condensate so produced is separated from 10 hydrogen in separator 10. Blower 11 in line 12 picks up the hydrogen and returns a portion thereof through line 13 back to evaporator 2, while the remaining hydrogen is disposed of through line 14.

15 The condensate from separator 10 is forced by pump 15 in line 16 through heating coil 17 in furnace 6, through transfer line 18 to evaporator 19 in which all but a residue boiling substantially above the boiling range of the original oil fraction 20 passing through the dehydrogenator is vaporized under superatmospheric pressure. The residue, which is of tarry nature, is withdrawn through line 20 and discarded through line 21.

The vapors, consisting essentially of aromatic 25 and paraffinic hydrocarbons, are allowed to expand through release valve 22 in line 23 to effect vaporization of entrained liquid. The resulting dry vapors are heated in coil 24 located in cracking furnace 25 to an effective non-catalytic cracking 30 temperature between about 500° and 750° C. In the first part of the coil the vapors may be heated relatively gently to an incipient cracking temperature of the order of about 450° C., and in the second part of the coil they are quickly 35 heated from the incipient cracking temperature to the effective cracking temperature, at which point they are held for the necessary length of time to effect the desired cracking of the paraffins, which time, depending upon the exact effective 40 temperature, may vary from less than a second to about 60 seconds. At the end of the cracking period the vapors are quenched with a suitable quenching medium, such as water, or hydrocarbons, preferably boiling below the boiling 45 range of the aromatic hydrocarbons contained in the cracked vapors such as pentanes or a substantially paraffinic recycle stock, etc. The quenching fluid is introduced through line 26 into transfer line 27 through which cracked vapors 50 are conveyed to a fractionating system shown as fractionator 28.

This fractionating system may comprise several fractionating columns, absorber, stabilizer, rectifier, circulating system for absorption oil, etc. Normally I separate five fractions from 55 fractionator 28: a heavy tar fraction boiling above the boiling range of the aromatic fraction, the tar being discarded through line 21; an aromatic fraction, usually boiling approximately within 60 the boiling range of the vapor fraction passing through dehydrogenator 7; an aliphatic fraction consisting essentially of olefines and paraffins boiling below the aromatic fraction comprising pentane and/or heavier hydrocarbons; a 3 to 5 carbon hydrocarbon fraction including olefines; and a waste gas fraction comprising ethane and lighter gases which goes through line 45 to a gas plant not shown. If desired the aromatic fractions and the pentane and/or heavier fraction 65 may be combined, particularly if the fractionation is followed by a selective solvent extraction to separate aromatic from non-aromatic hydrocarbons as will be described.

The aromatic fraction may be conducted 70 through line 29 and cooler 30 to storage tank 31.

Or it may be directed through lines 29 and 32 to fractionator 33 to be separated by fractional distillation into any desired number of fractions having high concentrations of aromatic hydrocarbons. Such fractions are indicated in the 5 drawing as light, medium, and heavy aromatic fractions, which are taken from fractionator 33 through lines 34, 35, and 36, coolers 37, 38, and 39, and run into run-down tanks 40, 41, and 42 respectively.

If it is desired to produce aromatic fractions substantially free from non-aromatic components, the aromatic fraction produced in fractionating system 28 may be conveyed through line 29 to extraction unit 43, in which non-aromatic impurities are removed as raffinate, while the aromatic extract goes through lines 44 and 29 to storage as hereinbefore described. The raffinate may be conveyed through lines 43, 62, and 63, pump 15 in line 16, etc. to the non-catalytic 20 cracking unit, or disposed of in other ways as hereinafter described.

The 3 and 5 carbon hydrocarbon fraction produced in fractionating system 28 proceeds through lines 46 and 47 to polymerizer 48 which is charged 25 with a suitable polymerizing catalyst as hereinbefore described. Olefines contained in this fraction are polymerized. The resulting mixture is transferred through line 49 to fractionator 50, where the polymers are separated from the unreacted 30 portion, the latter going through lines 50' and 23 to the non-catalytic cracking unit. The polymers may be fractionated to separate desirable 35 from undesirable polymers, the undesirable polymers returning through line 51 to the catalytic cracking unit to be depolymerized, while the desirable polymers enter hydrogenator 53 through line 52 together with an amount of hydrogen from line 55 and scrubber 54, which scrubber serves to remove sulfur compounds, particularly 40 hydrogen sulfide, and other acidic substances, e. g. arsenic oxides, said amount being sufficient substantially to saturate the polymers. If desired all of the polymers may go through lines 52' and 52 to the hydrogenator 53. Hydrogen in line 55 in excess of that required to saturate the polymers is conducted through line 55' to storage. Hydrogenated polymers proceed through cooler 56 in line 57 to separator 58 for the separation 45 of unreacted hydrogen and then pass through line 59 to tank 60. Unreacted hydrogen is withdrawn through line 61.

A portion or the whole of the non-aromatic pentane and heavier fraction produced in fractionating system 28 together with the raffinate 55 from extraction unit 43 and line 43' may be continually returned through lines 62, 63, and 16, pump 15, coil 17, line 18, evaporator 19, and line 23 to cracking coil 24 for recracking. For reasons hereinbefore discussed I prefer, however, to 60 conduct at least a major portion of this fraction through lines 62, 64 together with the raffinate from extraction unit 43 to the aforementioned catalytic cracking system, which comprises coil 65 in furnace 66, transfer line 67, and catalytic 65 cracking chamber 68. In coil 65, the fraction is vaporized and heated to the necessary cracking temperature which may vary from about 300° to 600° C., depending upon the type of catalyst used. The heated vapors are then passed over the catalyst at a rate to effect substantial conversion of the olefines, while leaving the paraffins largely unchanged and to form a substantial amount of 70 3 to 5 carbon olefines. The cracked vapors are introduced through line 69 into a fractionating 75

system shown as fractionator 70, where they are fractionated to produce: a waste gas fraction consisting essentially of ethane and lighter which is discarded through lines 71 and 45; a 3 to 5 carbon fraction which goes through lines 72 and 47 to polymerizer 48; a pentane and heavier fraction comprising largely paraffins which is preferably returned through lines 73, 74, 63, and 16, pump 15, etc. to the non-catalytic cracking system, or a portion of which may go through lines 73, 75, pump 76* in lines 76 and coil 65 to the catalytic cracking chamber 68 if desired; and a tar fraction which is withdrawn through tar line 77.

An alternate method of handling the pentane and heavier fraction produced in the fractionating systems 28 and 70 is to conduct them together with the raffinate from extraction unit 43 through lines 62, 78, and 73, 79, 78, respectively to a solvent extraction unit 80, where olefines are separated from paraffins, olefines being pumped by pump 76' in line 76 to the catalytic cracking unit, and paraffins going through lines 81, 74, 63, 16, pump 15, etc. to the non-catalytic cracking system. In this last manner the maximum amount of 3 to 5 carbon olefines for producing polymers which are especially valuable for the manufacture of high antiknock gasoline and the like is obtained, with the least contamination of the aromatic fraction, the least amount of gas and tar losses, and the least amount of coking difficulties.

It shall be understood that the particular flow diagram hereinbefore described is merely illustrative and that modifications of the various units such as the dehydrogenation unit, the cracking units, the fractionating units, the extracting units, etc. as known in the art but not shown in the diagram are within the spirit of this invention. For instance the catalytic polymerization unit may be replaced by non-catalytic thermal polymerization unit, or by a combination of catalytic and non-catalytic units as described in my co-pending application, Serial No. 86,122, filed June 19, 1936, and the unreacted hydrocarbons issuing from the polymerizer, instead of returning to the non-catalytic cracking zone or zones just mentioned, may be discarded or disposed of in some other suitable manner. Or the aromatic fraction prior to refractionation in fractionator 33 may be subjected to a refining treatment for instance by treatment with various chemicals such as sulfuric acid, alkali hydroxide, clay, etc. to remove sulfur compounds or to improve color and gum stability, odor, and so forth.

55 I claim as my invention:

1. The process for treating a hydrocarbon distillate containing naphthenes and paraffins comprising contacting said distillate oil with a dehydrogenating catalyst at an elevated temperature under time and pressure conditions selectively to dehydrogenate said naphthenes without substantially cracking said distillate and without substantially converting paraffins to olefines thereby converting naphthenes to aromatics and liberating hydrogen, separating the liberated hydrogen from the resultant mixture of aromatics and paraffins, subjecting said mixture to a non-catalytic vapor-phase cracking treatment under conditions to convert a major portion of the paraffins into light olefines, boiling below the original boiling range of the distillate, without substantially changing the nuclei of the aromatics and fractionally distilling the resultant cracked mixture to separate an aromatic fraction boiling essentially within the boil-

ing range of the original distillate from said light olefines.

2. The process for treating a hydrocarbon distillate containing naphthenes and paraffins comprising contacting said distillate oil with a dehydrogenating catalyst at an elevated temperature under time and pressure conditions selectively to dehydrogenate said naphthenes without substantially cracking said distillate and without substantially converting paraffins to olefines thereby converting naphthenes to aromatics and liberating hydrogen, separating the liberated hydrogen from the resultant mixture of aromatics and paraffins, subjecting said mixture to a non-catalytic vapor-phase cracking treatment under conditions to convert a major portion of the paraffins into light olefines, including olefines of 5 and less carbon atoms, said light olefines boiling below the original boiling range of the distillate, without substantially changing the nuclei of the aromatics, fractionally distilling the cracked mixture to separate therefrom: an olefinic fraction comprising hydrocarbons with less than 6 carbon atoms, a tar-free aromatic fraction having substantially a boiling range within that of the original oil, and an intermediate substantially non-aromatic fraction comprising olefines and paraffins, subjecting at least a portion of said intermediate fraction to a catalytic cracking treatment under conditions to convert a substantial part of the olefines contained therein to lower boiling hydrocarbons while leaving the paraffins in said fraction largely unchanged and returning unconverted paraffins to the non-catalytic cracking treatment.

3. The process for treating a hydrocarbon distillate containing naphthenes and paraffins comprising contacting said distillate oil with a dehydrogenating catalyst at an elevated temperature under time and pressure conditions selectively to dehydrogenate said naphthenes without substantially cracking said distillate and without substantially converting paraffins to olefines thereby converting naphthenes to aromatics and liberating hydrogen, separating the liberated hydrogen from the resultant mixture of aromatics and paraffins, subjecting said mixture to a non-catalytic, vapor-phase cracking treatment under conditions to convert a major portion of the paraffins into light olefines, including olefines of 5 and less carbon atoms, said light olefines boiling below the original boiling range of the distillate, without substantially changing the nuclei of the aromatics, fractionally distilling the resultant cracked mixture to separate an aromatic fraction boiling essentially within the boiling range of the original distillate from said light olefines, separating from said aromatic fraction a fraction consisting essentially of non-aromatic hydrocarbons, and returning the same to the non-catalytic cracking treatment.

4. The process of claim 1 in which the hydrocarbon distillate is a gasoline distillate.

5. The process of claim 1 in which the hydrocarbon distillate is a gasoline distillate having a boiling range not exceeding about 50° C.

6. The process for treating a hydrocarbon distillate containing naphthenes and aliphatics comprising contacting said distillate with a dehydrogenation catalyst at an elevated temperature under time and pressure conditions selectively to dehydrogenate said naphthenes without substantially cracking them, thereby liberating hydrogen, without substantially changing the composition of the aliphatics, separating the liberated

hydrogen from the resultant mixture of aromatics and aliphatics, subjecting the said mixture to a non-catalytic vapor phase cracking treatment under conditions to convert a major portion of aliphatics into lower boiling hydrocarbons, including olefines of 5 and less carbon atoms, without substantially changing the nuclei of the aromatics, separating from the cracked mixture: an olefinic fraction comprising 3 to 5 carbon hydrocarbons, a tar free aromatic fraction having substantially a boiling range of within that of the original oil, and an intermediate non-aromatic fraction comprising olefines and paraffins, subjecting at least a portion of said intermediate fraction to a catalytic cracking

treatment under conditions to convert a substantial portion of the olefines to 3 to 5 carbon hydrocarbons, while leaving the paraffins largely unchanged, returning unconverted paraffins to the non-catalytic cracking treatment, subjecting the 3 to 5 carbon hydrocarbons from the non-catalytic and catalytic cracking treatments to a polymerization treatment under conditions to convert olefines to polymers, fractionating the resulting polymers, hydrogenating a portion thereof with hydrogen from the dehydrogenation treatment, and returning the remaining portion to the catalytic cracking treatment. 5 10

ARTHUR HALLAM BOULTBEE. 15
